Primary Examiner — Ramzi S Almatrahi*(74) Attorney, Agent, or Firm* — Brake Hughes Bellermann LLP(57) **CLAIM**

The ornamental design for a video camera rig, as shown and described.

DESCRIPTION

FIG. 1 is a perspective view of a video camera rig;
FIG. 2 is an enlarged perspective view of an indicated area 2 of FIG. 1;

FIG. 3 is a top view thereof;

FIG. 4 is a bottom view thereof; and,

FIG. 5 is a side view thereof.

The broken lines depict portions of a video camera rig in which the design is embodied that form no part of the claimed design. The dot-dash lines denote boundaries of the claim and form no part of the claimed design.

1 Claim, 5 Drawing Sheets(56)
